Primary Examiner — David G Muller*Assistant Examiner* — Christina Gabrielle Cosden(74) *Attorney, Agent, or Firm* — Lambert Shortell & Connaughton; David J. Connaughton, Jr.; Justin P. Tinger(57) **CLAIM**

The ornamental design for a gate latch, as shown and described.

DESCRIPTION

FIG. 1 is a perspective angled front view of the gate latch, which embodies my design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

Portions of the drawings shown in broken lines form no part of the claimed design.

The dash-dot-dash broken lines represent the boundaries of the claimed design and form no part of the claimed design.

1 Claim, 7 Drawing Sheets(56)
